US00D781795S

(12) **United States Design Patent** (10) **Patent No.:** **US D781,795 S**
(45) **Date of Patent:** **** Mar. 21, 2017**

(54) **ELECTRONICS BOX**

(71) Applicant: **Verizon Patent and Licensing Inc.**,
Arlington, VA (US)

(72) Inventors: **Simon Waterfall**, San Francisco, CA
(US); **Suri B. Medapati**, San Jose, CA
(US); **Gregory A. James**, Phoenix, AZ
(US); **Brian G. Heintz**, White Salmon,
WA (US); **Kelvin Leung**, Menlo Park,
CA (US); **Gadi Amit**, San Mateo, CA
(US); **Susan McKinney**, San Francisco,
CA (US); **Jinwoo Kim**, San Francisco,
CA (US); **Byron B. Hsieh**, San
Francisco, CA (US); **Denise Myers**,
Washougal, WA (US)

(73) Assignee: **Verizon Patent and Licensing Inc.**,
Basking Ridge, NJ (US)

(**) Term: **15 Years**

(21) Appl. No.: **29/531,179**

(22) Filed: **Jun. 23, 2015**

(51) LOC (10) Cl. **14-03**

(52) U.S. Cl.

USPC **D14/125**

(58) **Field of Classification Search**

Primary Examiner — Randall Gholson

(57) **CLAIM**

The ornamental design for an electronics box, as shown and described.

DESCRIPTION

FIG. 1 is a front isometric view of an exemplary representation of our new design;

FIG. 2 is another front isometric view of the exemplary representation thereof;

FIG. 3 is a bottom isometric view of the exemplary representation thereof;

FIG. 4 is another bottom isometric view of the exemplary representation thereof;

FIG. 5 is another bottom isometric view of the exemplary representation thereof;

FIG. 6 is front view of the exemplary representation thereof;

FIG. 7 is a back view of the exemplary representation thereof;

FIG. 8 is a first side view of the exemplary representation thereof;

FIG. 9 is a second side view of the exemplary representation thereof;

FIG. 10 is a top view of the exemplary representation thereof; and,

FIG. 11 is a bottom view of the exemplary representation thereof.

The broken lines depict portions of the electronics box that form no part of the claimed design.

1 Claim, 5 Drawing Sheets
